US00D839740S

(12) **United States Design Patent** (10) **Patent No.:** **US D839,740 S**
(45) **Date of Patent:** **** Feb. 5, 2019**

(54) **PUSH BUTTON CLOSURE**

(71) Applicant: **Stolle Machinery Company, LLC**,
Centennial, CO (US)

(72) Inventors: **Dennis C. Stammen**, Brookville, OH
(US); **Patrick K. McCarty**, Dayton,
OH (US)

(73) Assignee: **Stolle Machinery Company, LLC**,
Centennial, CO (US)

(**) Term: **15 Years**

(21) Appl. No.: **29/637,830**

(22) Filed: **Feb. 22, 2018**

(51) LOC (11) Cl. **09-07**

(52) U.S. Cl.

USPC **D9/454**

(57) **CLAIM**

The ornamental design for a push button closure, as shown and described.

DESCRIPTION

FIG. 1 is a top perspective view of the push button closure;
FIG. 2 is another top perspective view of the push button
closure;

FIG. 3 is a bottom perspective view of the push button
closure;

FIG. 4 is another bottom perspect of the push button closure;

FIG. 5 is a top plan view of the push button closure;

FIG. 6 is a bottom plan view of the push button closure;

FIG. 7 is a side elevational view of the push button closure;
and,

FIG. 8 is a section view of the push button closure taken in
the direction of line 8-8 shown in FIG. 5.

1 Claim, 7 Drawing Sheets
